METHOD FOR CRACKING OILS.

Application filed August 13, 1923. Serial No. 656,990.

This invention relates to an improved method for cracking heavier hydrocarbon oils for the production of lighter hydrocarbon oils therefrom. More particularly, 5 the invention relates to an improved method of cracking heavier oils or distillates of a kerosene like character in a continuous manner in a tubular cracking still, and to an improved tubular cracking still adapted for 10 use in the carrying out of the process.

In the cracking of heavier oils in a tubular cracking still, or in a tubular cracking still of the so-called tube and tank construction, the heavier oil is passed through 15 a tubular cracking still with the tubes arranged in a furnace or heating flue and with the oil progressively heated during its passage therethrough. When the oil is heated to the cracking temperature it undergoes 20 cracking in a progressive manner. The cracking operation may be completed in the tubes so that the cracked oil is discharged directly from the tubular still to a vaporizing still or chamber or to a condenser for 25 the condensation of the cracked oil in the form of a so-called synthetic crude; or the cracking operation may be in part carried out during the passage of the oil through the tubes and in part in a reaction or di- 30 gestion chamber into which the oil from the heating and cracking coil is discharged and in which the oil is maintained at the cracking temperature to permit further cracking before the cracked oil is discharged 35 from the still.

In the operation of such tubular cracking stills, the cracking of the oil results in the formation of tar which tends to separate out on the heated walls of the still and to 40 form a deposit of "carbon" thereon which interferes with the heating of the oil in the tubes and tends to cause overheating of the tubes or hot tubes. In order to reduce this objectionable carbon deposit in the heating 45 tubes, digestion or reaction chambers have been combined with the heating coil to receive the heated oil and maintain it at the cracking temperature for considerable periods of time, thereby reducing the amount of cracking taking place in the tubes and the carbon deposit upon the walls of the tubes. When such digestion or reaction chambers

are not used, and when the cracking operation is completed in the heating tubes, the extent to which the cracking can be permitted to take place is limited by the formation of tar and carbon deposit on the walls of the tubes, particularly in the tubes through which the oil flows after considerable cracking has taken place therein and a 55 considerable amount of tar has been formed, so that it is necessary to limit the extent to which cracking is permitted to take place in the tubes to avoid objectionable carbon deposit therein. 60 65

According to the present invention, the operation of such tubular cracking stills is improved, so that the stills can be operated for longer periods of time before cleaning is required and so that the oil can be maintained in the still for longer periods of time, and the cracking carried to a further extent than would otherwise be feasible. 70

According to the present invention, we improve the operation of tubular cracking stills by the introduction therein, at an intermediate point, or at intermediate points, of the coils of the tubular still, of a solvent oil, or of solvent oils, which will mingle with the partially cracked oil flowing 80 through the tubular still and which will permit the degree of cracking to be continued over a longer period of time or carried to an increased degree. Such solvent oil or oils will dilute the partially cracked 85 oil in the still, as well as exert a solvent action thereon and particularly upon the tarry constituents, holding them in solution while further cracking takes place. The increased amount of oil also gives an increased velocity 90 through the tubes which further tends to reduce the danger of objectionable carbon deposit upon the tube walls. The increased time during which the oil can be maintained in the cracking coil and under cracking conditions without objectionable carbon deposit permits the time factor of cracking to be taken advantage of to a greater extent than would otherwise be possible, and the cracking of the initial oil can be carried to a correspondingly increased degree during the passage of the oil through the tubular cracking still. 95 100

The oil used as charging stock in the

process and apparatus of the present invention can be varied and heavier petroleum fractions can be used as the initial charging stock than would otherwise be feasible if the solvent oil or oils were not introduced at one or more stages of progression of oil through the heating coil. Somewhat lighter distillates and oils can also be used as the initial charging stock, and oils of a kerosene-like character can advantageously be employed.

The solvent oil or oils may in some cases be of the same character as the initial charging stock, and, in its broader aspects, the present invention includes the introduction of a solvent oil at one or more stages of progression of oil through the cracking coil, whether the oil so introduced is of the same character as the initial charging stock or of a different character.

We consider it more advantageous, however, to use a heavier charging stock initially and to introduce a lighter solvent oil after the heavier oil has undergone a partial cracking and in order to permit a further cracking of the heavier oil without objectionable carbon deposit on the tube walls. In particular, the solvent oils may be lighter distillates or fractions which will be cracked only to a limited extent and which will accordingly remain as more or less inert solvents while permitting continued cracking of heavier oil constituents. The solvent oil may however be one which will itself be cracked to a greater or less extent and may nevertheless exert a diluting and solvent action upon the oil flowing through the tubular cracking still.

The present invention relates more particularly to so-called liquid phase cracking of oils with the maintenance of a sufficient pressure upon the tubular cracking still to keep the oil or the greater part of it in a liquid state. The pressure employed can accordingly be varied with different oils depending upon the boiling point of the oil and the pressure necessary to maintain the oil to the necessary extent in a liquid state. Vaporization however may take place to a greater or less extent during the passage of the oil through the tubular still, and lighter vapors and gases may also be formed as a result of the cracking operation and remain in part in a gaseous state and be carried along through the coil with the liquid oil. Where the solvent oil is a lighter oil than the initial charging stock, the pressure should in general be sufficient to keep the solvent oil to a greater or less extent as a liquid. Lower pressures around 90 to 195 lbs. can be used with some oils while higher pressures of around 300 lbs. or even around 600 to 700 lbs. or higher may be used for the cracking of different oils.

The tubular cracking still itself can be

varied in its construction. For example, it may consist of a single-pass coil of a sufficient length to complete the cracking operation during the flow of the oil through the coil and the solvent oil may be introduced at one or more stages of the progression of the oil through the coil; or a plurality of coils may be employed, either in series or in parallel, and arranged in the same or separate furnaces, with provision for introduction of solvent oil at intermediate points of the coil or coils.

Where the cracking operation is completed in the coil or coils of the tubular still, the resulting cracked oil can be directly cooled and condensed, either under pressure or at atmospheric pressure, to give a synthetic crude which can then be re-distilled to obtain the desired gasoline and other distillates; or the cracked oil can be discharged into a vaporizing chamber, for example, at atmospheric pressure, and the heat contained in the oil utilized for vaporizing the lighter fractions of the cracked product which may be fractionally condensed.

Instead of completing the cracking operation in the coil itself, the partially cracked oil may be introduced into an insulated chamber or into a heated chamber and maintained at the cracking temperature and pressure to continue the cracking operation, after which the cracked oil may be cooled to give a synthetic crude or discharged to a vaporizing still or chamber and the heat of the oil utilized for vaporizing the lighter fractions of the oil, for example, as above mentioned. Where the solvent oil is introduced at one or more intermediate points of the cracking coil, the cracking operation can be carried to a much further extent in the coil without objectionable carbon deposit, and, in addition, the cracking operation can be still further continued in the digestion chamber by holding the cracked oil therein for a further period of time.

It will be evident that the size of the coil and the point or points of introduction of solvent oil, as well as the amount of such oil or oils introduced, can be varied, depending upon the pressure and temperature of the oil, the character of the oil and solvent, and the time factor necessary for the most efficient cracking of the charging stock under the conditions of operation. Different charging stocks will require somewhat different conditions of pressure and temperature for efficient cracking and will stand cracking to varying degrees, but in general the introduction of solvent oil, according to the present invention, will permit the cracking operation to be continued beyond the point otherwise feasible while nevertheless permitting the maintenance of the necessary conditions of temperature and pressure. The rate of circulation can also be

varied, depending upon the character of the oil, the size of the coil, the amount of the solvent oil and the time required to carry the cracking operation to the desired degree. 5 The rate of circulation will however increase with the introduction of the solvent oil and this increased velocity will further tend to reduce the danger of carbon deposit on the tubes.

10 Where the cracked oil is vaporized or distilled and fractionally condensed, the fractions so obtained, or certain of them, may advantageously be returned for use as charging stock and as solvent oil in the further carrying out of the process, thus making the process more or less cyclic in character. 15

The invention will be further described in connection with the accompanying drawing 20 showing, in a somewhat conventional and diagrammatic manner, an arrangement of apparatus embodying the invention and adapted for the practice of the process of the invention; but it will be understood that 25 the invention is illustrated thereby but is not limited thereto. The showing of the drawing is largely diagrammatic and conventional and not to scale, being partly in the nature of a flow sheet.

30 In the apparatus illustrated, a series of three coils 1, 2 and 3 is arranged in a single furnace together with a preheating coil 4, each of these coils being made up of a series of pipes connected at their ends by return 35 bends (not shown) and so arranged that the oil flows in a single-pass successively through the individual pipes of the coil.

The three cracking coils and the preheating coil are arranged in four flues or heating 40 chambers 5, 6, 7 and 8 of a furnace having a fire-box 9 with oil or gas burner 11 and having an outlet connection 10 to the flue or stack. A side connection 12 permits the return of part of the stack gases from near the 45 outlet of the furnace chamber 5 and their reintroduction into the vertical flue 13 where they will mix with the products of combustion from the fire-box thus giving a low temperature of the gases where they first come 50 in contact with the tubes and giving an increased velocity of the gases over the tubes, thus increasing the heating effect and maintaining a more nearly constant temperature in the coils of the first pass of the furnace in 55 the chamber 5. The return of a regulated amount of flue gas can be effected by a steam jet or blower (not shown).

Feed oil is supplied to the preheating coil 60 through the feed line 15. The preheated oil flows from the preheater coil to the first cracking coil 1 through the connecting pipe 14. Regulating valves 16 and 17 permit bypassing of part of the feed directly to the first cracking coil where this is desired, 65 while by closing the valve 17, the feed will

all pass first through the preheater and then through the cracking coil 1. From the cracking coil 1, the oil flows through connecting pipes 18 and 19 to the second coil 2 and from thence through connecting pipes 70 20 and 21 to the third cracking coil from which the cracked oil flows through the line 24.

Provision is made for introducing a solvent oil into the cracking still through the line 22, this oil mixing with the oil flowing 75 from the first coil 1 to the second coil 2. Provision is also made for the addition of a further amount of solvent oil through the line 23 to the oil passing from the second to 80 the third cracking coil.

The cracked oil leaving the tubular cracking still through the line 24 passes through the expansion valve 25 where its pressure is reduced to atmospheric or to a predetermined pressure above atmospheric and the expanded oil and vapors pass to the expansion chamber 26. In this expansion chamber which is conventionally shown, but which in practice will be of appropriate size, 85 the heat of the cracked oil is used in vaporizing the lighter constituents which pass off through the heat exchangers 39 and 38 and the connecting pipes 31, 40 and 41 to the condenser 42. From the condenser the distillate from the synthetic crude passes 90 through the gas separator 43 and the pipe 45 to a place of storage, while the gases pass off through the line 44 to a place of gas storage or use (not shown). 95

The unvaporized portion of the cracked oil is drawn off from the expansion chamber through the line 27 to the cooler 28 and is then pumped by the pump 29 to a storage tank 30. This unvaporized residue or tar 105 may be further fractionated or distilled for the recovery of heavier distillates, etc., therefrom.

The charging stock and solvent oil are supplied from suitable storage or supply tanks indicated at 33, 35 and 37. The charging stock in the tank 33 is indicated as a cut or fraction of 35° Bé. which may be obtained from the distillation of crude oil or in part from the synthetic crude produced by the cracking process or by other cracking process. This charging stock is pumped by the pump 32 to the supply line 15 and thence to the preheating coil in the furnace. The solvent oil in tanks 35 and 37 is indicated respectively as at 38° Bé. cut or fraction and a 41° Bé. fraction. The solvent oil indicated as 38° Bé. is pumped by the pump 34 through the heat exchanger 38 and then through the line 22 to a point intermediate the first and second cracking coils where it enters and admixes with the oil passing through the coils. 110

The solvent oil indicated as 41° Bé. is similarly supplied from the tank 37 by the 115 120 125 130

pump 36 and is forced through the heat exchanger 39 and the line 23 to a point intermediate the second and third cracking coils where it enters and admixes with the partially cracked oil entering the third coil.

The synthetic crude distillate, or the synthetic crude itself, if the latter is cooled without partial vaporization, is supplied through the line 48 to the pump 49 and 10 pumped into the rerun still 47 from which the successive fractions are condensed in a condenser 50 and collected in a receiver 51. The distillate from this rerun still may be cut into fractions corresponding to the desired gasoline fraction and the fractions indicated respectively as 41° Bé. cut, 38° Bé. cut and 35° Bé. cut, these respective cuts or fractions being distributed through the lines 55, 54, 53 and 52 respectively from the receiver 37. Additional charging stock and solvent oil may be supplied from extraneous sources, such as from distillates from crude oil or distillates from other cracking processes. The residue from the rerun still is 25 drawn off through 57 to a fuel storage 58.

When the still is first charged, and before the oil has been heated sufficiently to cause cracking to take place, the oil may be returned to the storage tank 33 by closing the 30 valve 25 and opening the valve 59 which permits the oil to return through the cooler 60 to the storage tank 33. When the desired temperature and pressure have been reached in the cracking coils, the valve 59 is closed 35 and the valve 25 gradually opened to permit discharge of the synthetic crude or cracked oil into the expansion chamber 26.

The cracking operation, when once established, may be continued for relatively long 40 periods of time. The charging stock will be supplied through the line 15 to the pre-heating coil from which the preheated oil will flow through the first cracking coil 1. The oil partly cracked in this coil is then admixed with solvent oil of 38° Bé. supplied through the line 22 and the resulting mixture passes through the cracking coil 2. The cracked oil flowing from the second coil 2 is then admixed with further solvent oil 45 of 41° Bé. supplied from the tank 37 through the line 23 and the resulting admixture then passes through the third cracking coil where the cracking operation is completed. The resulting cracked oil or synthetic crude is 50 then cooled to give a synthetic crude or is partially vaporized by utilizing the heat which it contains and the vapors separately condensed.

It will be noted that the flow of the oil 60 through each of the coils is generally counter-current to the flow of the gases so that the hottest gases come in contact with the tubes containing the hottest oil. It will also be noted that there is a decreasing 65 temperature gradient in the furnace such that

the oil charged to the cracking coils is first subjected to the highest temperature in the coil 1 located in the heating chamber 5 while the partially cracked oil with admixed solvent oil is subjected to progressively lower 70 temperatures in the coils 2 and 3 and the preheating coil 4 is in the heating chamber 8 at a somewhat lower temperature. This construction and arrangement permits the highest heat to be applied to the fresh oil 75 and permits the partially cracked oil with admixed solvent oil to be subjected to heating gases at a somewhat lower temperature so as to prevent excessive overheating of the oil while nevertheless maintaining the oil 80 at a cracking temperature and permitting further cracking to take place.

The solvent oil supplied at one or more intermediate points of the tubular cracking still may be preheated to the cracking temperature or to a somewhat lower temperature. If it is not preheated to the cracking temperature it will exert a cooling action on the partially cracked oil with which it is admixed. Some cooling of the partially 90 cracked oil may be desirable to prevent overheating and to reduce objectionable carbon formation; and by regulating the temperature and amount of the solvent oil, this cooling effect as well as the solvent action of the 95 oil can be regulated. By introducing the solvent oil at a temperature somewhat below that of the oil undergoing cracking and by obtaining the cooling action as well as the solvent action of the oil, a somewhat lesser quantity of the solvent oil can be used. In the apparatus illustrated the solvent oils are heated in the heat interchangers 38 and 39 by the vapors given off from the cracked oil or synthetic crude; but it will be evident that this heating may be supplemented and the solvent oil preheated to any desired temperature by additional heating means (not shown) and its temperature and the cooling 100 effect upon the oil in the still thereby regulated. Where the solvent oil is preheated to the cracking temperature it will exert its solvent action without cooling of the oil 110 passing through the cracking coils.

It will be evident that the amount of solvent oil introduced can be varied, as well as the nature of the solvent oil and the stage of the progress of the oil through the coil at which the solvent oil is introduced. In general, the amount of solvent oil should be sufficient to hold in solution all or practically all of the tar formed from the cracking operation so as to prevent objectionable super-saturation of the oil with tar and resulting tendency toward objectionable carbon deposit on the walls of the heating tubes; while nevertheless permitting the cracking operation to proceed considerably beyond the point which would be feasible if the solvent oil were not used. By using a 115 120 125 130

solvent oil which is not cracked to any considerable extent under the conditions of temperature and pressure maintained in the still, the further cracking of the charging stock will be permitted while the partially cracked charging stock is admixed with the added solvent oil, and the solvent oil will in such case act largely to dilute the partially cracked charging stock and to permit further cracking thereof while holding the tar in solution and preventing objectionable supersaturation of the oil with the tar. The introduction of solvent oil in regulated amount permits obtaining the necessary time factor for the most efficient cracking of the charging stock at the desired pressure and temperature while preventing objectionable deposit of pitch and carbon during the prolongation of the cracking operation and giving as the product of the cracking operation a more or less completely cracked solution of the charging stock in the solvent oil.

The pressure in the apparatus can be regulated by the valve 25 between the still and expansion chamber although the pressure will be influenced by the rate of feed of the charging stock or of the solvent oil entering the still.

The utilization of the heat of the cracked oil for effecting a partial vaporization or distillation of the oil results in economy of operation which is further increased by utilizing the heat of the vapors to preheat the solvent oil supplied to the still. The cracked oil or synthetic crude, either through partial vaporization by the heat which it contains, or by condensation of the cracked oil as a whole and subsequent redistillation, can be fractionated into the desired gasoline cut and into one or more solvent oil cuts as well as a heavier gravity cut which can be returned to the original charging stock. The cracking operation itself may thus supply part of the initial charging stock for further operation as well as solvent oil for use in the further carrying out of the process, although it will be evident that fresh charging stock and fresh solvent

oil can be used without return of any of the products from the cracking operation.

It will thus be seen that the present invention provides for a prolonged continuity of operation of a coil cracking still with increased efficiency of the cracking operation. It will also be seen that the invention is of more or less general application in connection with tubular cracking stills where the cracking operation is carried out in the coils of the tubular still, and that it makes possible the carrying of the cracking operation to a greater extent and for a longer period of time than would otherwise be feasible.

We claim:

1. The improvement in the cracking of oil in tubular cracking stills which comprises forcing the oil in a single-pass through a cracking coil and heating the oil therein to a cracking temperature under a high pressure, introducing a solvent oil into the partially cracked oil at one or more intermediate stages of its progress through the cracking coil, and preheating the solvent oil by heat interchange with the cracked oil or with distillates therefrom.

2. The improvement in the cracking of oil in a tubular cracking still which comprises forcing the oil in a single-pass through a cracking coil and heating the oil therein to a cracking temperature under a high pressure, introducing a solvent oil into the partially cracked oil at one or more intermediate stages of its passage through the cracking coil, releasing the pressure on the cracked oil and vaporizing therefrom by its self-contained heat the lighter constituents, passing said lighter constituents into heat interchanging relation with the solvent oil to preheat the same, and recovering from said constituents further amounts of charging stock and solvent oil adapted for further use in the carrying out of the process.

In testimony whereof we affix our signatures.

CHARLES L. PARMELEE.
EDWARD W. ISOM.
